Alonzo C. Arnold

United States Patent Office.

ALONZO C. ARNOLD, OF NORWALK, CONNECTICUT.

Letters Patent No. 70,065, dated October 22, 1867.

IMPROVEMENT IN MACHINE FOR CROSSING BATS FOR FELTING.

The Schedule referred to in these Letters Patent and making part of the same.

TO ALL WHOM IT MAY CONCERN:

Be it known that I, ALONZO C. ARNOLD, of the town of Norwalk, county of Fairfield, and State of Connecticut, have invented a new and useful improvement in the mode of constructing Crossers to Felting Machines; and I do hereby declare that the following is a correct description thereof, reference being had to the accompanying drawing, and to the letters of reference marked thereon.

The nature of my invention consists in the construction and arrangement of an improved mode of crossing the fibre to form the batting for felt cloth.

To enable others to make and use my invention, I will proceed to describe the same. The drawing—

Figure 1, represents a side view and part section of the crosser.

Figure 2, a plan view of the same.

The framework, with doffer comb-cylinders, and other attachments, I construct in the usual manner. My improvements consists in the arrangement of a series of horizontally travelling endless belts or bands A, as shown in the drawing, figs. 1 and 2, containing a number of diagonally inclined sharp teeth B, to take hold of and support the transverse bat, or sliver, as it proceeds from the doffer-comb, in its passage across the fibrous bat or sliver that travels along longitudinally from the cylinders L of the carding machine, and when the whole area of this sliver has crossed the same the whole distance, and is broken off at the sunk part M of the doffer D, the pin C, in the end of the doffer, lifts up the arm E, which actuates the levers and various arrangements N N N, and causes the whole of the falling or dividing rods F to descend simultaneously on the longitudinal bat, and by means of the vertical slotted vibrating-lever G, rotating arm H, and pin I, presses off, and by the inclined and forward movement of the lever G, disengages, the transverse bat from the teeth B of the bands A, allowing it to fall on the longitudinal travelling-bat, as it passes along from the carding-machine cylinder, causing the same to be connected therewith in the manner required. And when this is accomplished, the spring K, or its equivalent, presses on the top of the lever or arm E, instantly lifting up the faller-rods F, and supports them till the next revolution of the doffer and pin C causes the same operation to be repeated. The novelty and utility of this improved movement for the purpose required are in its simplicity and effectiveness.

What I claim as my invention, and desire to secure by Letters Patent, is—

The arrangement of the series of travelling endless-toothed bands A, and dividing fallers F, or their equivalents, in the manner as and for the purpose described.

Also, in combination with the arm E and levers N, the slotted vibrating-lever G, rotating arm H, and pin I, as and for the purpose set forth.

ALONZO C. ARNOLD.
